OIL FILTER

Jesse A. Baldwin, Spooner, Wis.

Application April 13, 1936, Serial No. 74,202

4 Claims. (Cl. 210—131)

This invention relates to improvements in filters, and more particularly to oil filters for use with lubricating systems of the pressure type.

Among the objects of the invention may be noted the provision of an oil filter which is characterized by features of simplicity in design, durability and efficiency in operation, and which is further inexpensive in construction and installation; the provision of an oil filter of the stated character, which may be readily emptied of foreign matter and/or sludge collected from the oil under treatment, and in which access may be had to the filter element for cleaning and/or renewal in simple manner; the provision of an oil filter in which the entering oil is caused to follow in a path such that heavy particles of impurities or foreign matter are separated from the oil prior to the oil reaching the filter element, thus to reduce the possibility of clogging the filter element.

With these and other objects in view, this invention consists in certain novel features of construction, combination and arrangement of parts to be hereinafter more fully described and claimed.

For a complete understanding of my invention, reference is to be had to the following description and accompanying drawing, in which—

Figure 1 is a vertical sectional view illustrating an oil filter constructed in accordance with my invention.

Figure 2 is a top plan view illustrating the device.

Figure 3 is a sectional view taken on the line 3—3 of Figure 1.

Figure 4 is a sectional view showing a modified form of filtering element readily adaptable to the type of filter shown in Figure 1.

Referring in detail to the drawing, the numeral 1 indicates a casing adapted to be vertically arranged and have its upper end fully open and equipped with a marginal flange 2 for forming a seat for a head 3, the latter being detachably secured to the flange by fasteners 4. A gasket 5 is interposed between the head and flange to provide an effective seal. Formed on and extending at right angles to the head is an attaching bracket 6 capable of permitting the casing 1 to be readily adapted to a support so that the casing will be placed in a vertical position. The bottom of the casing has formed thereon a drain neck 7 equipped with a valve seat 8 and a bore 9, a portion of which is screw threaded to receive a screw threaded plug 10 to which the stem 11 of a valve 12 is secured. Drain ports 13 are formed in the neck 7 and communicate with the bore 9 between

the valve seat 8 and the screw threaded plug 10. By threading the plug outwardly with respect to the drain neck, the valve 12 will be engaged with the seat 8 thereby closing the casing 1 against emptying.

Inlet and outlet passages 14 and 15 are formed in the head 3, the outlet passage 15 being disposed centrally of the head and arranged vertically while the inlet passage 14 is disposed horizontally and extends radially of the head, with its inner end terminating short of the center of the head. The passages for a portion of their length are internally screw threaded to permit a lubricating system to be readily connected to this device so that the oil of the system during its circulation will be compelled to pass into and out of the casing. An inlet port 16 is formed in the head 3 and has one end communicating with the passage 14 adjacent the inner end of the latter. The port 16 opens into the casing 1 and, by reference to Fig. 1, is inclined downwardly of the axis of the passage 14, and by reference to Fig. 2, is also inclined laterally of the axis of the passage 14, the downward and lateral inclinations being each approximately 45°. Hence, the direction of flow of oil entering through the passage 14 is substantially reversed, with the incoming oil entering the casing at an angle downwardly inclined to the horizontal passage 14, and also laterally inclined with respect thereto.

A substantially cylindrical strainer 17 is located in the casing 1 and has its lower end closed by a wall 18 engaged by a coil spring 19, the latter having seating engagement with the bottom wall of the casing.

Mounted on the upper end of the screen 17 is an end cap or diaphragm 20 provided with a centrally arranged opening 21 located directly under the outlet passage 15 and secured to the walls of the opening 21 is the upper end of a substantially cylindrical screen 22. The lower end of the screen 22 terminates adjacent the wall 18 of the screen or strainer 17. The screen 22 is positioned substantially centrally of the screen 17. An annular offset 23 is formed on the diaphragm and seats in an annular groove 24 formed on the head 3, thereby permitting the diaphragm to block the passage of oil from the inlet passage 14 to the outlet passage 15 and compel said oil to pass through the screens 17 and 22 before reaching the outlet passage 15. The space between the screens 17 and 22 is filled with a filtering material 25 which may be of any desired character so that the oil after passing through the screen 17 must pass through the filtering material 25 before pass-

ing through the screen 22. The oil on leaving the outlet passage 15 will be substantially free of foreign matter, such matter being left in the casing 1 where it may be drained therefrom by un-

5 seating the valve 12.

By reference to Fig. 1, it will be seen that the peripheral portion of the cap 20 is sloped or inclined downwardly, such portion being arranged beneath the outlet end of port 16 and spaced 10 slightly therefrom. Hence, oil entering the casing under pressure through the downwardly and laterally inclined port 16 is directed against the sloped surface of the strainer cap 20, such tending to throw the oil outwardly against the circular 15 inner wall of the container 1. The lateral inclination of the port 16 causes the oil to be directed against the aforesaid casing wall at a forwarding angle, that is to say, an angle less than 90°. Accordingly, the oil is given movement in a circular path, such movement being hereinafter referred to as "swirling" movement, with the result that heavy particles of foreign 20 matter are separated by centrifugal force, and tend to fall to the bottom of casing 1 for subsequent removal therefrom.

The casing being readily detachable from the head will permit access to the screens and filtering material so that said screens may be readily cleaned and new filtering material placed therein 30 when needed.

Referring to Figure 4 a modified form of filtering means to be arranged between the screens 17 and 22 is shown and consists of a fibrous covering 28 in which is positioned a filtering material 29. The covering is wound into substantially spiral formation and positioned between the screens 17 and 22, this being clearly shown in Figure 4. The material employed for making the covering as well as the filtering agent may be of 40 any desired kind.

Having described the invention, I claim:

1. A filter comprising a substantially cylindrical casing, a head operatively secured thereto, the head having inlet and outlet passages there-45 through and an annular groove located between said inlet and outlet passages, a filter element in the casing arranged in the path of flow between the inlet and outlet passages, the filter element including an upper cap having an annular offset 50 and a downwardly sloped peripheral portion, means including said sloped cap portion for causing the entering fluid to be filtered to impinge against the inner wall of the casing at a forwarding angle, and spring means arranged between the 55 casing and the filter element and operative to yieldingly maintain the offset of the cap seated in the head groove.

2. A filter comprising a substantially cylindrical casing, a head operatively secured thereto, the 60 head having a horizontally arranged inlet passage and a vertically arranged outlet passage, a filter element in the casing arranged in the path

of flow between the inlet and outlet passages, the filter element including an upper cap element having a downwardly sloped peripheral portion, and the head being provided further with an inlet port communicating with the inner end of the 5 inlet passage and opening into the casing above the sloped portion of the cap element, said inlet port having an acute inclination downwardly and laterally with respect to the axis of the horizontally arranged inlet passage whereby fluid entering the casing is directed relatively outwardly against the sloped portion of the cap element and thence against the inner wall of the casing.

3. A filter comprising a casing having one end open, a removable head closing said casing and having an inlet and an outlet and an annular groove located between said inlet and outlet, a filter element including a cap member having an annular offset to engage in said groove and provided with an opening in communication with the outlet, an inner screen secured to the walls of the opening of the cap member, an outer screen surrounding the inner screen and secured to the cap member, a filtering medium located between the inner and outer screens, and spring means arranged between the casing and the filter element and operative to yieldingly maintain the offset seated in the groove and thereby to maintain the filter element in the path of fluid flow 20 between the filter inlet and outlet.

4. A filter comprising a substantially cylindrical casing, a head operatively secured thereto, the head having a horizontally arranged inlet passage and a vertically arranged outlet passage and an annular groove located between said passages, a filter element in the casing arranged in the path of flow between inlet and outlet passages, the filter element including a cap member provided with a central opening in communication with the outlet, an intermediate annular offset to engage in said groove, and a downwardly sloped peripheral portion, an inner screen secured to the cap member about the central opening, an outer screen surrounding the inner screen and secured to the cap member, a filtering medium located between the inner and outer screens, spring means arranged between the casing and the filter element and operative to yieldingly maintain the offset of the cap member seated in the head groove, the head being provided further with an inlet port communicating with the inner end of the inlet passage and delivering into the casing above the sloped peripheral portion of the cap member, said inlet port having an acute inclination downwardly and laterally with respect to the axis of the horizontally arranged inlet passage, whereby fluid entering the casing is directed relatively outwardly against the sloped portion of the cap element and thence against the inner wall of the casing.

JESSE A. BALDWIN.
